UNITED STATES PATENT OFFICE.

GEORGE S. ENGLE, OF PROVIDENCE, RHODE ISLAND.

SHIRT-BUTTON.

SPECIFICATION forming part of Letters Patent No. 777,191, dated December 13, 1904.

Application filed May 4, 1903. Renewed May 3, 1904. Serial No. 206,215. (No model.)

To all whom it may concern:

Be it known that I, GEORGE S. ENGLE, a citizen of the United States, residing at Providence, in the county of Providence and State 5 of Rhode Island, have invented certain new and useful Improvements in Shirt-Buttons, of which the following is a specification, reference being had therein to the accompanying drawings.

10 My invention relates to the class of buttons primarily adapted for use upon the bands of shirts and other articles of wearing-apparel and popularly known as "collar," "cuff," or "shirt" buttons. Besides the ends commonly 15 sought in structures of this kind it is desired hereby to provide a clamping means upon the button whereby the latter may engage bands with or without buttonholes.

To the above ends my invention consists in 20 the construction and combination of parts hereinafter described, and illustrated in the accompanying drawings, wherein—

Figure 1 is a side elevation of my new button; Fig. 2, a central vertical section; Fig. 3, 25 a top plan view of the same. Figs. 4, 5, 6 are similar views, respectively, of a modified form of my new button; and Fig. 7 is also a modified form.

Like letters of reference indicate like parts 30 throughout the views.

As shown, my button comprises a post *a* and head *o*, of any convenient construction, rising from an upper clamping-plate *b*. The latter is provided with a socket *f* and upon 35 its under surface cavities *h*. One of its ends is folded over to embrace a pivot or pintle *g*. The pintle also engages, through a perforation therein, the lug *i* of a bottom clamping-plate *c*, upon whose upper surface is a ball or projection *d*, adapted to register in the socket *f* of the upper plate. Prongs *e* rise at intervals upon the plate *c*, adapted to register in the cavities *h*, above referred to.

My invention is above referred to in connection with a stationary post; but it is obviously applicable when the button-post carries

upon its bottom a transverse plate *m*, as shown in Fig. 5, by means of which the post has play. The plate *m* may be slidably engaged in any convenient manner with the upper 50 clamping-plate—for instance, as seen in Figs. 4, 5, and 6, where the plate *m* is shown as of elongated form corresponding to an opening in the plate, through which the plate *m* may be inserted, so as to occupy a position back of the said clamping-plate in which the opening is formed, and then by turning the said plate *m* at right angles, as seen in Fig. 6, the plate *m* can be slid up or down and yet is held against accidental separation and cannot be removed 60 till the same is brought coincident with the opening. When the parts are in their closed position, the projection *d* bears against this plate *m* and holds the parts against movement. 65

To apply my button, the clamping-plates are forced together, with the shirt or other band *s* intermediate the two, and the ball *d*, passing through the opening or buttonhole *t* of the fabric, registers in the socket *f*. 70

It will be noted that my structure dispenses with all pressure upon the neck, wear upon the buttonhole, accidental detachment, and reinforcement of the neckband.

The modifications to which my invention 75 is obviously adapted are to substitute for the hinge *g* a springy loop, as shown in Fig. 7, wherein the broken lines indicate the parts in disengaged position.

Having described my invention, what I 80 claim as new, and desire to secure by Letters Patent, is—

1. In a shirt-button, the combination with a post, of a clamping-plate carrying the same, and having a socket, a second clamping-plate 85 hinged to the first-mentioned plate and having a projection to engage in said socket and prongs to engage in cavities in the adjacent face of the first-mentioned plate, said post being adjustably connected to the first-mentioned plate. 90

2. A shirt-button comprising two plates

hinged together, one being double-walled and formed in one wall with a socket and in the other with an elongated opening, and the other with a projection to engage in said socket, 5 and a post passed through said opening and having a flange engaging the inner face of the wall in which said opening is formed whereby the post is slidably connected with

its supporting-plate, the said projection engaging said flange when the parts are closed. 10

In testimony whereof I have affixed my signature in presence of two witnesses.

GEORGE S. ENGLE.
